UNITED STATES PATENT OFFICE.

JAMES EVERITT, OF LONDON, ENGLAND.

WARDROBE RACK.

1,420,534.

Specification of Letters Patent. Patented June 20, 1922.

Application filed June 5, 1920. Serial No. 386,730.

To all whom it may concern:

Be it known that I, JAMES EVERITT, subject of the King of Great Britain, residing at 11-19 Lever Street, Goswell Road, London, in the county of Middlesex, England, have invented certain new and useful Improvements in Wardrobe Racks, (for which I have received patent in Great Britain, No. 11,270, May 7, 1914), of which the following is a specification.

The invention refers to the hanging of clothing from a bar, rod or tube in wardrobes, trunks, warehouses, and such like, and has for its object to provide a railway for a plurality of article hangers or runners which is so constructed as to be capable of folding when not in use to reduce the overall length thereof and extensible to maximum length when desired for the purpose of more 20 separately supporting such runners.

According to the invention such a bar or tube is built up of two or more hinged together parts adapted to open out and form a rigid length and to fold to reduce the 25 length, the one end of said bar or tube being rigidly attached to a suitable surface or support preferably the interior space of a wardrobe opened by a front door, the foldable extension swinging down when the door is 30 closed to lie slightly inwards of said door. The foldable extension may be fastened to the fixed part of said bar or tube by a catch device which may be either hand operated or automatic in action, or in the case of 35 a wardrobe or the like said extension may be supported by a bracket or other contrivance carried upon the inside of the wardrobe door. Said bar or tube may be fitted with a pull-out device in the form of a movable abutment moving to a position at the extreme 40 inner end of the rod or tube and behind all the garments, and extending forwardly by side rods to the extreme front of the fixed portion of the bar or tube, so that a hand- 45 pull on this pull-out device when the bar or tube is extended collectively pulls out the garment suspenders or runners.

The invention is represented diagrammatically by the accompanying drawings in 50 various forms differing only in constructional details, in which—

Figure 1 shows a side elevation of my invention.

Figure 2 is a cross sectional detail of the 55 clothes hanger tube.

Figure 3 is a plan view of the invention taken from beneath.

Figure 4 is a detail of the hanger connection between the sections of the tube.

Figure 5 is a modification showing the 60 hinged section swingable upwardly.

Figure 6 is a plan view of the invention applied to a wardrobe.

Figure 7 is a side elevation of the device shown in Figure 6.

In Fig. 1 is shown a side elevation of a clothes hanging tube formed of two parts a and c hinged together at d . The part a is fixed at a^2 to a surface or support and is the fixed part of the hanger tube, and the 70 part c is the extensible one swinging down for shortening the length into the position indicated by the dotted lines e and f is a mechanical catch comprising lever f^2 and stud f^3 adapted to engage and hold the extension when in use, this catch being hand operated for engagement and disengagement. 75

A cross section of the tube is represented in Fig. 2 suitable for internal runners forming the connectors between the clothes and 80 the tube, such a form of tube and runners being well known.

Fig. 4 a side elevation detail of how the extension part c swings down and the catch f operates, and with regard to Figs. 2 and 85 3 it may be pointed out that a^3 and c^2 are slots in the tube through which a depending portion of each runner projects.

Fig. 5 shows a similar elevation of Fig. 1 but with the extension part c arranged to 90 swing upwardly instead of downwardly in which case no mechanical fastening is needed to hold the two parts together in a straight line. In this representation a number of runners g are indicated within the 95 tube part a in order to illustrate that a dummy runner g^2 at the back of the whole of the supporting runners is connected forwardly by a pull-out device h in the form of side rods connecting at the front h^2 and 100 adapted for hand operation when the extension c is in use to pull the whole of the runners forward, so that the clothes can be well separated for inspection and detachment. 105

Figs. 6 and 7 show the application of the invention to a wardrobe. The tube parts of the clothes support are at a and c aforesaid and same are hinged together at d in accordance with Figs. 1 to 4, the 110

end a^2 being secured to the back of the wardrobe space opposite the front door x . This door is hinged at x^2 and opens in the usual way to open and close the space y of the wardrobe, and same may be fitted with a bracket s swinging to position as shown in Figs. 6 and 7 to support the extension c when in use, and against the inside of the wardrobe door, as indicated by the dotted line t . When said extension is folded as represented at w in Fig. 7, this bracket s being a modification of the mechanical means f , hereinbefore described.

As the slots a^3 , c^2 of the tube portions a and c are underneath it is possible to additionally support the tube part a by an oblique stay such as v shown in Fig. 7.

It is to be understood that the preferable form is one extension part such as c to the supporting rod or tube which can be arranged to swing either up or down out of use.

Having now described my invention what I claim and desire to secure by Letters Patent is:—

1. A wardrobe rack, comprising a tube formed of a plurality of hinged together parts adapted to open out to form a con-

tinued length and to fold to reduce said length means for fixing one of said parts to a support so as to carry the other part, devices for rigidly securing the foldable part to the fixed part to make the tube rigid throughout its length and garment carrying runners slidable lengthwise within said tube.

2. A wardrobe rack, comprising a tube formed of a plurality of hinged together parts adapted to open out to form a continuous length and to fold to reduce said length, means for fixing one of said parts to a support so as to carry the other part, means for locking said parts rigidly together, garment carrying runners slidable lengthwise within said tube, and a puller out device for said runners comprising a member arranged within said tube and engaging the runners and a handle for said member.

In testimony whereof I have hereunto set my hand in presence of two subscribing witnesses.

JAMES EVERITT.
